UNITED STATES PATENT OFFICE

ROY E. ADAMS, OF INDIANAPOLIS, INDIANA, ASSIGNOR, BY MESNE ASSIGNMENTS, TO
J. D. ADAMS MANUFACTURING COMPANY, OF INDIANAPOLIS, INDIANA, A CORPOR-
ATION OF INDIANA

ROAD GRADER

Application filed December 31, 1926. Serial No. 158,307.

It is the object of my invention to produce a mounting, as for the mold board of a road grader, which mounting will permit the ready adjustment of two relatively movable parts and will hold the two parts in various positions of adjustment without undesirable lost motion, and which can be constructed without necessity for expensive methods of manufacture involving extreme accuracy.

10 I have illustrated my invention as applied to the mounting of a road-grader mold board adapted to be attached to the semicircle of the road grader. In accordance with my invention the mold board is pivotally attached 15 to the semicircle through universal joints, preferably of the ball-and-socket type, and a link is provided for holding the mold board in various positions of angular adjustment about the axis of the ball-and-socket joints. 20 The link is also mounted through ball-and-socket joints which permit tight clamping without the necessity for close alinement.

The accompanying drawings illustrate my invention: Fig. 1 is a plan view of a road grader to which my invention is shown as applied; Fig. 2 is a generally horizontal section on the line 2—2 of Fig. 5 through one of the links by means of which the mold board is adjusted; Fig. 3 is a horizontal section on 25 the line 3—3 of Fig. 5 through the axis of pivotal mounting of the mold board; Fig. 4 is a perspective view of a washer which operates with the link to hold it in various positions of adjustment; Fig. 5 is a vertical section through the mold board close to one of its 30 points of attachment to the semicircle; Fig. 6 is a fragmental side elevation of the mold board in partial section at one of the points where the mold board is attached to the semicircle; and Fig. 7 is a side elevation of the 35 mold board with parts of a reinforcing member broken away to illustrate the means provided for securing adjustment of the mold board longitudinally of itself relative to the semicircle.

In the road grader shown in the drawings, a main frame 10 is supported through front wheels 11 and rear wheels 12. A draw bar 13 is supported from the main frame through 40 suitable adjusting mechanism including lift

arms 14 by means of which the draw bar may be raised or lowered. Pivotally mounted on a vertical axis on the draw bar 13 is a semicircle 15 having downwardly extending legs 16 to the lower ends of which a mold board 17 is 55 attached. The details of construction of the road grader form no part of my invention and may be anything desired.

The customary method of attaching the mold board to the legs of the semicircle or to the equivalent parts has been to provide the mold board with a bracket adjacent each semicircle leg and to connect each of such brackets with its associated semicircle leg by means of a pivot pin or bolt. In order to 60 avoid the necessity for excessive accuracy in the construction of such a mold board mounting and at the same time to provide a mounting which will not bind, the pivot pins are made slightly smaller in diameter than the 65 holes through which they pass. This is satisfactory in eliminating binding but is objectionable in that it introduces lost motion between the parts and produces undesirable rattling and vibration which in time cause 70 excessive wear.

To overcome these objectionable features and at the same time to eliminate the possibilities of binding and to permit ready adjustment of the mold board, I secure the lower ends of the semicircle legs to the mold board through a universal connection. To this end, at points adjacent the lower ends of the semicircle legs I secure to the mold board 17, or to a reinforcing member 18 thereon, brackets 20. Each of these brackets is provided in a lateral face with a hemispherical depression adapted to receive the complementarily shaped flange 21 of a bushing 22 which may extend into a hole in the lower end of the semicircle leg 16. A bolt 23 passing through the bracket 20, the bushing 22, and the lower end of the semicircle leg approximately on the axis of the spherical depression of the bracket 20 serves to secure the mold board to 85 the semicircle. The holes in the bracket 20 and in the bushing 22 through which the bolt 23 passes are desirably somewhat larger than the bolt in order that the bolt will not bind in 90 such holes.

This method of attaching the mold board to the semi-circle permits the mold board to be mounted so that it is freely adjustable without any lost motion. The bolts 23 may be tightened to bring the mating spherical surfaces of the bracket 20 and flange 21 of the bushing 22 into firm engagement with each other without the production of any binding effect, for the bolts 23 are smaller than the holes through which they pass. Since the bolts need not be in exact alinement, the necessity for extreme accuracy is eliminated.

To hold the mold board in various positions of angular adjustment about the axis of its pivotal attachment to the semicircle, I provide the mold board adjacent each semi-circle leg with a link 25 which is pivotally attached to the mold board near the upper edge thereof and which may be secured in various positions to the semicircle leg. To avoid any binding and still to secure the mold board firmly in its various positions of adjustment, I prefer to mount the links as illustrated in Figs. 2 and 5.

In the construction illustrated, each link 25 is attached to the mold board 17 through the medium of a bracket 26 secured to the mold board. One end of each of the links 25 is provided with a hemispherical depression adapted to receive a correspondingly shaped boss 28 on the bracket 26. A bolt 29, passing through the boss 28, the end of the link 25, and preferably through a washer 30, serves to secure the link 25 to the bracket 26. The inner surface of the washer 30 is desirably spherical to conform to the engaging surface of the end of the link 25. The hole in the link 25 through which the bolt 29 passes is materially larger than the bolt in order to permit a certain universality of movement of the link relative to the mold board.

Secured to each of the legs 16 of the semi-circle 15 is a bracket 35 having a stud or bolt 36 which projects outward through a longitudinal slot 37 in the link 25 and is provided beyond the link with a nut 38. Located between the link 25 and the adjacent face of the bracket 35 I provide a washer 40 the construction of which is clearly indicated in Fig. 4. The washer 40 fits the stud closely so as to have no lost motion but may pivot thereon to follow the link 25 the angular position of which varies as it is adjusted. In the plane of the slot 37, the washer 40 is provided with two outwardly extending fingers 41 which enter the slot 37 and have a width substantially equal to that of such slot, thus serving to hold the link and washer in definite angular relationship. In a plane at right angles to that of the fingers 41, the washer 40 is provided with two outwardly projecting bosses 42, the exterior surfaces of which are conveniently cylindrical and are adapted to enter into one pair of a series of notches 43

provided on the inner face of the link 25. The fingers 41 preferably project outwardly beyond the bosses 42 in order that they will remain in the slot 37 when the nut 38 is loosened sufficiently to permit adjustment of the link.

The construction described makes it possible to secure the mold board firmly to its support without any lost motion and consequent rattling and vibration. At the same time it is not necessary to secure precise alinement of the various connections, since the spherical shape of the mating surfaces makes exact alinement unnecessary.

If desired the mold board 17 may be provided with two sets of brackets 20, as shown in Fig. 7, thus making possible an adjustment of the mold board longitudinally of itself. The reconnecting of the mold board and semicircle after such adjustment is facilitated by the ball-and-socket construction.

I claim as my invention:

1. In a road grader, the combination of a mold board, a supporting member therefor, means for pivotally attaching said mold board to said supporting member on a single axis fixed relatively to said supporting member, said means including mating parts having spherical engaging surfaces, an adjusting link pivotally connected to said mold board through a universal connection, and means for holding said link in various positions of adjustment relative to said supporting member to vary the inclination of said mold board.

2. In a road grader, the combination of a mold board, a supporting member therefor, means for pivotally attaching said mold board to said supporting member on a single axis fixed relatively to said supporting member, an adjusting link pivotally connected to said mold board through a ball-and-socket connection, and means for holding said link in various positions of adjustment relative to said supporting member to vary the inclination of said mold board, said ball-and-socket connection including a ball-member on one of the parts which said connection connects, a socket on the other of such parts, said socket having an exterior spherical surface, a concave washer engaging such surface, and a bolt passing through said ball, socket, and washer for holding them together.

3. In a road grader, the combination of a mold board, a supporting member therefor, means for pivotally attaching said mold board to said supporting member, an adjusting link pivotally connected to said mold board, and means for holding said link in various positions of adjustment relative to said supporting member to vary the inclination of said mold board, said means including a washer rotatably mounted on said supporting member, said washer being provided with means engaging said link for holding said

washer and link in definite angular relationship, said link being provided with a series of transverse notches, a boss on said washer adapted to enter any of said notches, and means for holding said washer and link in engagement with said boss in one of said notches.

4. In a road grader, the combination of a mold board, a supporting member therefor, means for pivotally attaching said mold board to said supporting member on a single axis fixed relatively to said supporting member, and adjusting link, means for pivotally connecting said link to said mold board, said means including a ball member secured to said mold board, a cooperating socket rigid with said link, said socket having a convex spherical surface, a concave washer engaging such spherical surface, and a bolt passing through the ball member, socket, and washer to hold them together, and means for holding said link in various positions of adjustment relative to said supporting member to vary the inclination of said mold board.

5. In a road grader, the combination of a mold board, a rigid supporting member therefor, said supporting member being angularly adjustable about a vertical axis, means for pivotally attaching said mold board to said supporting member at horizontally spaced points and on a single axis fixed relatively to said supporting member, each of said means including mating parts having spherical engaging surfaces, an adjusting link pivotally connected to said mold board, and means for holding said link in various positions of adjustment relative to said supporting member to vary the inclination of said mold board.

6. In a road grader, the combination of a mold board, a rigid supporting member therefor, said supporting member being angularly adjustable about a vertical axis, means for pivotally attaching said mold board to said supporting member at horizontally spaced points, each of said means including mating parts having spherical engaging surfaces, and means for holding said mold board at various inclinations.

7. In a road grader, the combination of a mold board, a support therefor including two spaced downwardly projecting legs, said legs being provided with aligned holes near their lower ends, a ball member carried by each of said legs and having a projection adapted to enter the associated hole, sockets carried by said mold board in positions to receive said ball members respectively, a bolt passing through each of said legs and the adjacent ball member and socket, and means for holding said mold board at various inclinations.

8. In a road grader, the combination of a mold board, a rigid supporting member there-

for, said supporting member being angularly adjustable about a vertical axis, means for pivotally attaching said mold board to said supporting member at horizontally spaced points, and means for holding said mold board at various inclinations, said attaching means including mating parts having spherical engaging surfaces and a bolt passing through such parts, said bolt having a limited freedom of movement transversely of itself in one of said mating members.

In witness whereof, I have hereunto set my hand at Indianapolis, Indiana, this 29th day of December, A. D. one thousand nine hundred and twenty six.

ROY E. ADAMS.
